CLAIM

The ornamental design for a table, as shown and described.

DESCRIPTION

FIG. 1 is a front perspective view of a table according to the new design;

FIG. 2 is a rear perspective view thereof;

FIG. 3 is a front view thereof, the rear, left side, and right side views being identical to the front view;

FIG. 4 is a top view thereof; and,

FIG. 5 is a bottom view thereof.

The broken lines in the drawings illustrate portions of the table that form no part of the claimed design.

1 Claim, 5 Drawing Sheets
